UNITED STATES PATENT OFFICE.

DIMMITT ROSS LOVEJOY, OF NEW YORK, N. Y., ASSIGNOR TO LOVEJOY DEVELOPMENT CORPORATION, OF NEW YORK, N. Y., A CORPORATION OF NEW YORK.

INDUCTANCE COIL.

Application filed August 14, 1924. Serial No. 732,021.

To all whom it may concern:

Be it known that I, DIMMITT Ross Lovejoy, a citizen of the United States, and a resident of the city, county, and State of New York, have invented certain new and useful Improvements in Inductance Coils, of which the following is a complete specification, the particular novel feature of my invention being specifically stated in the annexed claims.

It is well known that with the high frequency currents used in radio, the accuracy of tuning afforded by an inductance coil is impaired by the distributed capacity. Various methods for reducing the distributed capacity without diminishing the inductance have been devised, such for example as spider web, honeycomb, lattice weave and the like. Most of these winding expedients cannot well be used in winding a single layer cylindrical coil.

The object of my present invention is to construct a single layer cylindrical winding with minimum distributed capacity without impairment of inductance. The invention comprises a helical coil in which successive sections are radially staggered in such a manner as to separate the adjacent wires by a fixed distance except where they cross from one radius to another and to make the crossing in such a way as to reduce the capacity effect to the minimum.

In the accompanying drawing:

Figure 1 illustrates an axial view of a coil made according to my invention.

Figure 2 is a side elevation of the same.

Figure 3 is a detail of the coil.

Figure 4 is a preferred form of coil in which the periphery is cylindrical instead of polygonal.

Figure 5 is an alternative construction.

Referring to Figures 1 and 2 of the drawing, the wire 1, preferably enamel insulated, is crimped in such a manner that when wound, long sections alternating with shorter sections, will form this into a polygonal cylinder, the long sections forming the interior sides of the polygon and the short sections the exterior. When formed into a cylinder in this way, insulating cords 2 may be extended through the interstices and tied in knots as at 3 to securely and locally lock the assembled crossings in position. The coil thus becomes quite rigid and self-sustaining, which permits it to be

handled as a separate article of manufacture. Suitable flexible terminals may be attached to the end, as shown at 4. By reference to Figure 3 it will be seen that the wires cross each other at a considerably greater angle than they would if they went crisscross diagonally direct from one crossing to the next and that in between the crossings absolute parallelism at the proper minimum distance is maintained. In Figure 4 is shown the same idea applied to a circular coil. Here again the crossings are at a considerable angle while in between the crossings the wires run in parallel arcs. In Figure 2 I have shown at 5 a strip of insulating material which may be used as a means of supporting the coil, it being slid in between the two parallel layers, as shown in cross section in Figure 1. The coil may be slid along such a support to adjust its nearness to other elements. In Figure 5 I have shown the same method being used but with rigid separating pins 6 taking the place of the cord, the pins being supported on a circular ring 7. With such a frame, very thin wire may be wound onto coil 8 and still attain the functions sought by the present invention.

While my invention in its broadest sense is applicable both to the polygonal and the circular forms, no specific claim is made herein to the polygonal form as this will be made the subject of a separate application.

I claim:

1. An inductance coil in the form of a self-supported multi-turn helix of uniform diameter, in which the adjacent sections of successive turns are radially staggered and parallel with respect to each other.

2. An inductance coil in the form of a self-supported multi-turn helix of uniform diameter, in which the adjacent sections of successive turns are radially staggered and parallel with respect to each other, with free air space between the turns.

3. An inductance coil in the form of a self-supported multi-turn helix of uniform diameter, in which the adjacent sections of successive turns are radially staggered and parallel with respect to each other, and means for locking the turns in position.

4. An inductance coil in the form of a self-supported multi-turn helix of uniform diameter, in which the adjacent sections of successive turns are radially staggered and

- parallel with respect to each other, and means applied locally at the crossings for locking the turns in position. 30
5. An inductance coil in the form of a self-supported multi-turn helix of uniform diameter, in which successive turns cross each other from one radius to another and are parallel between crossings, and locking means composed of insulating material interposed in the angle of the crossings. 35
6. An inductance coil in the form of a self-supported multi-turn helix of uniform diameter, in which adjacent sections of successive turns are radially staggered and parallel with respect to each other, and insulating cords embracing the wires where they cross. 40
- 15 7. An inductance coil in the form of a self-supported multi-turn helix of uniform diameter, in which adjacent sections of successive turns are radially staggered and parallel with respect to each other, and insulating cords extending between the parallel wires and embracing the assembled crossings where the wires pass from one radius to another. 45
- 20 8. An inductance coil in the form of a self-supported multi-turn helix of uniform diameter, in which adjacent sections of successive turns are radially staggered and parallel with respect to each other, insulating supports embracing the assembled crossings where the wires pass from one radius to another, and a base to which the insulating supports are attached. 50
- 25 9. An inductance coil in the form of a self-supported cylindrical helix in which each turn is comprised of a series of sections of circular arc form, the adjacent sections of successive turns being staggered 40 radially with respect to each other and parallel to each other between crossings. 55
10. An inductance coil in the form of a self-supported cylindrical helix in which each of the adjacent turns are made up of circular arcs of alternately shorter and longer radii, those of shorter radii being adjacent to those of longer radii in the adjacent turns. 55
11. An inductance coil in the form of a multi-turn helix in which adjacent sections of successive turns are radially staggered and parallel with respect to each other, and supporting means for said coil in the form of a plate of insulating material inserted 55 between the inner and outer layers of one of the sections.

DIMMITT ROSS LOVEJOY.
